UNITED STATES PATENT OFFICE.

PIERRE T. GAUTIER, OF ST. LOUIS, MISSOURI.

SPARK-PLUG.

1,246,414.

Specification of Letters Patent. Patented Nov. 13, 1917.

Application filed November 22, 1912. Serial No. 132,755.

To all whom it may concern:

Be it known that I, PIERRE T. GAUTIER, a citizen of the United States of America, a resident of the city of St. Louis, State of Missouri, have invented certain new and useful Improvements in Spark-Plugs, of which the following is a full, clear, and exact description, reference being had to the accompanying drawing, forming a part of this specification.

My invention relates to a spark plug for use upon internal combustion engines, and it has for its object to provide a simple means constituting a part of the spark plug whereby the user may quickly and positively determine the delivery or non-delivery of an electric current to the spark plug. Briefly stated, the invention consists in arranging a switch between the electrical conductor receiving portion of a spark plug and one of the electrodes of the plug, said switch being a component of the plug and capable of providing indication of an electric current in a spark plug due to sparking when the switch is either opened or closed.

Figure I is a side elevation of my spark plug.

Fig. II is a vertical section through the plug.

Fig. III is a top view of the plug.

Fig. IV is a cross section taken on line IV—IV, Fig. I.

In the drawings:

1 designates the outer electrode which is preferably of the usual form, including the presence of a screw thread adapted to connect the spark plug to the cylinder of an explosive engine.

2 is an insulator mounted in the outer electrode 1 and secured thereto by a retaining bushing 3. All of these parts may be of any usual form as no invention *per se* is herein claimed for them.

4 designates an inner electrode mounted in the insulator 2, but extending only part way therethrough from the inner end of said insulator. 5 is a stem seated in the outer end of the insulator 2 and separated from the inner electrode 4. The stem 5 is prefer-

ably screw threaded to receive a binding nut 6 which serves to secure a conducting wire to the spark plug.

A and B designate the terminal members of a switch, through the medium of which the passage of an electric current from the stem 5 to one of the electrodes of the spark plug is controlled. In the form of switch I have shown the member A is dished and fits over the outer end of the insulator 2, and the switch member B is in the form of a band which encircles the insulator and is connected to the inner electrode 4 by a pin 7 extending transversely through the band, the insulator and the inner electrode. The switch terminal members A and B are placed in circuit with each other by a contact bar 8, which is pivoted to one of the members and is movable to and from contact elements carried by the other member, the said bar being preferably provided with a handle 9, by which it may be operated.

It will be apparent that when my spark plug is in service, and the switch is closed, the electric current delivered to the stem 5 will traverse the switch member A, the switch bar 8, the switch member B, the inner electrode 4, and jump from the latter to the outer electrode 1. It will also be obvious that when the circuit is broken by the separation of the free end of the switch bar from the switch member which receives said end, a spark will be produced if an electric current is passing through the spark plug from the conductor secured thereto, thereby affording knowledge of delivery of electric current to the spark plug.

While I have shown and described only a knife switch, it is obvious that other forms of switches might be utilized in lieu of a knife switch to accomplish the same purpose, and I, therefore, do not wish to be limited to the use of this particular kind of switch.

I claim:

1. A spark plug comprising an insulator, an electrode and a conductor-receiving member, both mounted in said insulator and separated from each other by a portion of the insulator, and a switch connecting said elec-

trode and conductor-receiving member; said switch having separable contact portions exposed to view exteriorly of the spark plug.

2. A spark plug comprising an insulator, 5 an electrode mounted in said insulator, a switch band fitted to said insulator and having connection with said electrode, a switch member seated on said insulator, a conductor

receiving member in the outer end of said insulator adjacent to the last mentioned 10 switch member, and a circuit breaking switch element interposed between said switch member and said switch band all of said switch members being components of the spark plug.

PIERRE T. GAUTIER.
